UNITED STATES PATENT OFFICE

109,671

DESIGN FOR AN ORNAMENTAL GRILLE FOR AN AUTOMOBILE RADIATOR

John Oswald, Lansing, Mich., assignor to General
Motors Corporation, Detroit, Mich., a corpora-
tion of Delaware

Application September 30, 1937, Serial No. 71,883

Term of patent 3½ years

To all whom it may concern:

Be it known that I, John Oswald, a citizen of the United States and a resident of Lansing, county of Ingham, and State of Michigan, have invented a new, original, and ornamental Design for an Ornamental Grille for an Automobile Radiator, of which the following is a specification, reference being made to the accompanying drawings forming a part thereof.

Figure 1 is a front elevation of an ornamental

grille for an automobile radiator showing my novel design.

Figure 2 is a side view thereof.

Figure 3 is a section on the line 3—3 of Figure 2 showing one-half of the design only.

I claim:

The ornamental design for an ornamental grille for an automobile radiator as shown.

JOHN OSWALD.
